UNITED STATES PATENT OFFICE

2,539,750

REVOLVING DOOR

Holger G. E. Nordin, Chicago, Ill.

Application August 23, 1946, Serial No. 692,675

1 Claim. (Cl. 20—18)

1

This invention relates to improvements in revolving doors of the partially collapsible panic-proof type. One object is to provide an improved door that is neat and attractive in appearance, that will operate in a smooth and efficient manner, that is of light weight but very durable construction, relatively inexpensive to manufacture, that is wear-resistant and not easily put out of order.

A still further object is to provide a revolving door that is readily assembled and installed, one wherein all parts are easy of access for repair, replacement, lubrication or cleaning when necessary.

Other objects, novel features and advantages of arrangement, construction and design comprehended by the invention are hereinafter more fully pointed out or made apparent from the following description of a preferred embodiment as illustrated in the accompanying drawings wherein like reference characters denote corresponding parts throughout.

In the drawings:

Fig. 1 is a view partly in side elevation, partly in section, and with certain parts broken away, of a single locking unit of one of the four wings of a revolving door constructed in accordance with the invention.

Fig. 2 is a vertical sectional view through Fig. 1 on the line 2—2.

Fig. 3 is an enlarged fragmentary sectional view of Fig. 1 showing a portion of the release mechanism.

Fig. 4 is an horizontal cross sectional view, enlarged, through Fig. 1 on the line 4—4 and showing a portion of the center post structure.

Fig. 5 is a top plan view of the top and bottom door yokes showing the wings and doors in inoperative position.

Fig. 6 is a top plan view of the door yoke employed, and,

Fig. 7 is a view partly in elevation, partly in section and with parts broken away, of one wing with the door proper shown in dotted lines.

The reference numeral 1 denotes a central tubular shaft formed with an angular slot 2 near its lower end, said end resting upon and being secured to a tubular stub shaft 3, the opposite end of shaft 1 receiving and being secured to another stub tubular shaft 4. Adjustably received in the shaft 1 previous to its assembly with stub shafts 3, 4 is the rod 5 extending below the lower end of stub shaft 3 and normally into the hollow flanged base block 6 arranged in the socket 7 in floor 80, the bore in said block 6 being in line with

that of the stub shaft 3. The said rod 5 extends through and beyond the upper end of stub shaft 4 and has fast thereupon a flanged collar 8 operatively and freely received in the ball bearing 9 secured in the track 10 built in the structure served in conventional manner. Clearance is provided above the upper end of rod 5 to permit it to be raised by means of its handle 11 extending out through slot 2 in shaft 1 a distance to effect the withdrawal of the lower end of said rod 5 from the said block 6, said handle being screwed into a threaded socket in rod 5 after same is located in shaft 1 and movable from end to end of said slot 2.

Each stub shaft is provided with a plurality, preferably four, vertical ribs 12 spaced ninety degrees apart and received at the outer end of each shaft is a spider 13 or 14 each provided with four radial arms 15 extending outwardly, ninety degrees apart, the ends 16 of upper and lower arms being bent toward each other and each end formed with a perforation 17, said spiders being recessed complimentary to said ribs 12 to receive same.

The upper face of each spider 13, 14 is grooved to form a track 18 composed of a plurality of connected segments, four in number and of equal size, the points of connection of said segments being in the planes of the said arms 15, round pegs 19 of the same diameter as said ribs 12 and terminating at an elevation common therewith are disposed centrally of said segments and therefore equidistant from each other and each peg a common distance from the two ribs adjacent thereto. Received for travel in said track 18 are the four pins 21 carried approximately centrally of the slightly elongated heads 22 at the inner ends of span arms 23, said heads formed peripherally with semi-circular notches 24, 25, 26, the notch 24 of each head being in the plane of its arm and the notches 25, 26 upon opposite sides thereof and equidistant from notch 24, said notches being formed complimentary to said ribs and pegs 12, 19; the distance between notches 24 and 25 or 26 being the same as that between a rib 12 and its adjacent pegs and adapted for engagement therewith singly as said head is moved laterally as clearly shown in Fig. 5.

The said span arms 23 when engaged with the ribs 12 are parallel with the said arms 15 and immediately adjacent thereto and extend materially therebeyond and are connected together, said top span arms to the corresponding span arms at the base by the brace bars 27. Also connecting each span arm 23, top and bottom, to brace bars

27 are the top and bottom escutcheon plates 28, 29, said pairs of plates being connected to each other also by the auxiliary brace bars 30 spaced inwardly from brace bars 27, said pairs of plates also receiving and supporting the wings 31 of the door. The escutcheon plates are formed with elongated perforations 32 extending from their inner ends outwardly marginally and terminating in enlarged angularly disposed portions 33 in the plane of arms 15 to provide clearance therefor.

The members of each pair of escutcheon plates receive therebetween a longitudinally extending angular frame having the inner end 34 formed with a vertical recess 35 complimentary to and freely receiving a rib 12 of the center post 1 thus forming a hinge; a base 36 from which perforate partitions 37, 38 rise and an outer end 39 terminating in the toe 40, said partitions 37, 38 operatively receiving a sleeved bolt 41 having a head 42 extending slightly beyond partition 39 for engagement, in projected position, with the perforate portion 17 of the downturned end 16 of arm 15, an expansion coil spring 43 about said bolt abutting said head and a nut 44 in partition 37, said bolt being connected by an angular coupling member 45 to a bell-crank-lever 46 fulcrumed upon pin 47 connecting said escutcheon plates, said bell-crank-lever pivotally engaging an elongated block 48 slideable vertically in the frame base 36, said block being connected by pitman 49 to a similar structure provided in the opposed pair of escutcheon plates. Arranged in the frame base 36 in a recess 50 is an expansion coil spring 51 abutting a plug 52 and dog 53 having a tooth 59 that may be engaged with a notch 60 in block 48 to retain said block in raised position thus through the medium of top and bottom levers 46 and connections, including springs 43 under compression, retaining the bolts 41 out of engagement with the ends 16 of arms 15. Should the door become locked in stationary position, however, with one or more persons confined therein one or more wings may be collapsed by manual movement of the handle 61 of dog 53 extending through an elongated slot 62 and by means of which said dog may be retracted to release block 48 permitting expansion of springs 43 and seating the heads of bolts 41 in perforations 17 thus affording a passageway through the locked or defective door.

The structure is now, as shown in Figs. 1 and 4, in inoperative position. Pressure now applied to this wing 31 will move same with the connected escutcheon plates and direct connections laterally away from arm 15 and connections without rotation of shaft 1 but affording a passageway through the door. Continued application of force to this wing will cause it to contact the adjacent wing in its path of movement and cause collapse of same through engagement with one of the levers 63, one upon each side of said escutcheon plates,

fulcrumed to said plates upon opposite sides of said block 48, the inner ends 64 of said levers engaging the recessed portions 65 of said blocks for raising same as said levers are moved toward said plates until notch 60 of block 48 is engaged by dog 53. The normal position of the doors is shown in Fig. 7 with bolts 41 engaging perforations 17 of the downturned ends 16 of arms 15. Manual operation of one or both levers 63, moving same toward an escutcheon plate will also break the operative connection between wings 31 and shaft 1 and when the upper block 48 is in line with tooth 59 of dog 53 the spring 51 will move same into supporting engagement with said block. Re-assembly is effected by manual movement of handle 61 of said dog through slot 62 to disengage said dog from said block whereupon spring 43 will, after wing 31 and connected escutcheon plates have been manually moved into alignment with an arm 15, force bolt 41 again into arm perforation 17. To remove the door the central shaft and connections are raised to clear the lower end of rod 5 from block 6 and the leaves and escutcheon plates disconnected from arms 15 and the latter removed from shaft 1.

What is claimed is:

In a revolving door, a central rotary shaft, spiders fast to the ends of said shaft, span arms adjustably associated with said spiders, wings carried by said span arms, escutcheon plates connecting and carried by said span arms and wings, bolts carried by said escutcheon plates yieldingly engaging said spiders, adjustable notched blocks associated with said escutcheon plates, connection between said blocks and bolts, means for releasably retaining said blocks in inoperative position with said bolts retracted with respect to span arms, said means including spring-pressed toothed dogs engaging the notches in said adjustable blocks, handles for said dogs, and levers carried by said escutcheon plates and fulcrumed thereto, said levers engaging said blocks for raising same when said levers are moved in one direction, the levers of each escutcheon plate disposed in the path of movement of either adjacent escutcheon plate when same is displaced from normal position under pressure, said levers adapted also for manual movement.

HOLGER G. E. NORDIN.
